VOLUME RANGE EXPANDER CIRCUIT

Paul F. G. Holst, Oaklyn, N. J., assignor to Radio Corporation of America, a corporation of Delaware

Application August 31, 1939, Serial No. 292,789

1 Claim. (Cl. 179—171)

The present invention relates to volume range expander circuits for audio frequency amplifiers, and has for its primary object to provide an improved volume range expander circuit of the character referred to, which may be adjusted to operate over a useful portion of a predetermined volume range of expansion for various signal levels with a given amplifier, and which may be turned off and on without objectionable change in signal volume or sound output level from a sound producing device connected with the controlled amplifier.

In the usual volume range expander circuit for electric phonograph amplifiers, a potentiometer type of volume control device is provided to control the amplitude of signals applied to the expander circuit. It has been found that a major portion of the operating movement or control range of such potentiometer devices provides no effective control of the expander action. Therefore, it is a further object of the present invention to provide a volume range expander circuit which is not subject to this undesirable operating condition and which gives substantially full control of the range of dynamic expansion over the full range movement of the control element of the circuit for a range of signal levels ordinarily encountered in audio frequency signal conveying circuits and amplifiers.

It is also an object of the present invention to provide a volume range expander circuit which operates in response to variations in the average amplitude of applied signals to provide volume range expansion effectively in connection with phonograph reproducing systems, and which may be adjusted to respond within a limited useful control range to variations in the amplitude of recorded signals on phonograph records.

For phonograph record operation, or for operation in response to any signals which may vary in amplitude, the selected ranges of expander control may be considered, for example, with regard to the expander circuit response to (1) a strong or relatively high amplitude passage on a loud or high average amplitude record; (2) a weak or relatively low amplitude passage on a loud or high average amplitude record; (3) a loud or relatively high amplitude passage on a weak or low average amplitude record; and (4) a weak or relatively low amplitude passage on a weak or low average amplitude record.

The same consideration of signal strength variation for expander operation may be given in connection with any audio frequency amplifier having a variable amplitude signal supply.

The maximum gain required from the expander amplifier under item 3 above should be such that this type of signal will cause full expansion within the limits of operation of the expander circuit, that is, will open up the expander to maximum. Additional gain is unnecessary and may even be harmful and, as provided in known expander circuits, causes difficulties in the adjustment of the expander control and signal distortion.

The minimum gain required is that referred to under item 1 above, for which condition of operation it must be possible to adjust the expander control means to a position providing minimum expansion, for example, by turning the volume expander control knob fully counter-clockwise, but not off, and in that position to produce a slight expansion action, such as 1-to-2 db. for strong or high amplitude passages on a loud or high average amplitude record or signal.

It is, therefore, a further object of the present invention to provide a volume range expander control circuit operative in accordance with the foregoing conditions, whereby full volume range expansion action may be obtained on all types of phonograph records with a minimum of ineffective control action in the operation of a control device or input potentiometer means for the volume range expander circuit.

In a volume range expander circuit arranged in accordance with the invention, as in known circuits of this nature, a diode rectifier device is employed for rectifying the applied signals to produce a controlling voltage which varies in accordance with variations in the average amplitude of the said applied signal. In connection with this type circuit, it is also a further object of the present invention to provide a volume range expander control circuit wherein substantially all of the voltage output of the diode rectifier is made available for control purposes through an improved connection and coupling arrangement for the diode rectifier, and wherein a relatively light load is provided by the diode rectifier, whereby direct coupling to the output circuit of a preceding amplifier tube may be utilized in the expander system.

The invention will, however, be better understood from the following description when considered in connection with the accompanying drawing, and its scope is pointed out in the appended claim.

In the drawing.

Figure 1 is a schematic circuit diagram of an audio frequency amplifier system for phonograph

record reproduction provided with a volume range expander control circuit embodying the invention.

Figure 2 is a schematic circuit diagram of a portion of the circuit of Fig. 1 with certain of the circuit elements and connections rearranged whereby the operation of the circuit of Fig. 1 may be more readily apparent, and

Figure 3 is a graph showing curves illustrative of an operating characteristic of the system of Fig. 1.

Referring to Fig. 1, the amplifier system shown by way of example comprises a source of audio frequency signal such as an electric phonograph pickup device 5 connected through an adjustable control network 6 and an output circuit comprising a high signal potential lead 8 and a low signal potential lead 9 to an output volume control device 10-11. The lead 9 of the phonograph pickup output circuit is grounded, as indicated, to the chassis and to the metallic motor board or other frame member of the phonograph mechanism indicated by the dotted enclosure 12.

The amplifier system further includes a combined amplifier and volume expander tube 15 having a signal input grid 16 coupled to the volume control output contact 11 through a coupling capacitor 17 and having a bias supply resistor 18 connected back to a tap 19 between two sections 20 and 21 of a self-bias resistor. The latter is connected between the cathode 22 and chassis or ground 23 which is also the negative side of the anode potential supply system. The positive lead of the anode supply system is indicated at 24.

The output anode of the tube is indicated at 25 and is coupled in the usual manner to a succeeding amplifier represented by the rectangle 26, and a sound producing or output device such as a loudspeaker, indicated at 27, the latter being connected to the output circuit 28 of the amplifying system.

The combined amplifier and volume expander tube 15 is preferably of the type having a separate gain controlling grid indicated at 30 to which variable gain controlling potentials with respect to cathode are applied through the delay filter comprising a series resistor 31 and a shunt capacitor to cathode 32, from a supply lead 33. The tube is also provided with a screen grid 34 for the gain controlling grid 30 and a suppressor grid 29 connected to cathode. This tube, for example, may be of the type known commercially as the RCA 6L7 pentagrid amplifier.

The amplifier and phonograph pickup circuit thus far described is representative of any audio frequency amplifier to which a volume expander control circuit embodying the invention may be applied. The volume expansion control circuit includes a potentiometer device connected across the signal input circuit 8-9 in shunt thereto and comprises three resistor or impedance sections 35, 36 and 37 in series between the high and low sides of the circuit, the center section 36 having an adjustable output tap connection 38 thereon which is connected to a separate volume expander amplifier and detector channel 39 through a lead 40 on the high potential side and chassis or ground connection on the low potential side. The purpose and relative values of resistor sections will hereinafter be discussed.

The expander amplifier and detector channel preferably includes a buffer amplifier tube 41 having a signal input or control grid 42 connected to the input lead 40 and having a cathode 43 connected to chassis or ground through a suit-

able bias source such as a self-bias resistor 44, as indicated. The output anode 45 of the amplifier tube is provided with an anode coupling resistor 46 and coupling capacitor 47 through which amplified signal energy is applied to a diode rectifier 48 in such a manner that the diode 48 and an output resistor 50 therefore are connected effectively in parallel with the amplifier output resistor 46 through the coupling capacitor 47.

By inverting the diode, that is, by connecting the diode anode 51 and one terminal 52, of the output resistor 50, to ground as indicated at 53, while the cathode 54 is connected to the high signal potential terminal 55 of the output resistor 50 through a lead 56, substantially all of the D. C. potential resulting from signal rectification may be developed across the single resistor 50 and may be applied to the control circuit 33.

This arrangement provides a highly effective and efficient voltage supply circuit having an improved sensitivity, while being greatly simplified with respect to the circuit and circuit components required, over the usual diode rectifier circuit. The connection between the diode cathode 54 and the supply lead 53 is provided through a series filter resistor indicated at 57.

Since the diode anode 51 is connected to ground 53 and therefore to the ground 23 and to the negative end of the self-bias potential source 20-21 of the amplifier tube 15, the increasing positive output potential developed at the terminal 55 with respect to ground, in response to signals appearing across the input circuit 8-9 from the signal source 5, causes the potential of the control grid 30 of the amplifier 15 to be raised in a positive direction above ground. Depending upon the adjustment of the potentiometer input contact 38, the grid potential may be raised to or above the value of the potential provided by the resistors 20 and 21 as an initial negative bias on the grid 30.

Since the connections are such that the potential across the diode output resistor 50 is in opposition to the bias potential provided by the source 20-21, the effect of increased signal amplitude is to increase the positive bias between grid 30 and cathode 22 in opposition to the negative biasing potential between the cathode 22 and ground 23, that is, to reduce the initial negative bias potential, and if permitted to increase sufficiently high, the grid 30 may be driven up to a positive range of operation.

The operation of the circuit will be further understood from a consideration of Fig. 3 wherein the curves 63, 64 and 65, drawn with logarithmic coordinates, represent input-output characteristics for different fixed values of gain in the amplifier. The curve 64 represents the highest permissible gain and curve 63 represents the lowest gain in the operating range of the amplifier. The various intermediate values of gain between the two limits represented by the curves 63 and 64 may be obtained by adjustment of the biasing potential applied to the control grid 30 of the amplifier 15.

Since the control channel operates in response to signals from the main signal channel, the control voltage applied to the electrode 30 increases with an increase in the signal input voltage. The corresponding values of the input-output characteristic will consequently be located in a curve corresponding to different amplifier gains and the oscillating input-output curve will

appear as shown at 60. The signal input below the value indicated by the line 61 does not produce sufficient control voltage to affect the gain of the amplifier, while signal voltages higher than those indicated by the line 62 serve to hold the gain at its maximum value by reason of the grid current flow, as hereinafter pointed out.

A high degree of volume expansion is obtained between a certain initial biasing potential value and zero bias corresponding to a point in the operation when the rectified signal bias equals the initial bias. This is represented by the curve 60 between the limits of signal input at the dotted lines 61 and 62, the initial biasing potential being such that the amplification is substantially constant up to the signal input value indicated by the line 61. At signal input voltage values higher than those represented by the line 62, no appreciable increase in amplification is secured, since the control grid 30 reaches zero bias for an input signal amplitude corresponding to the line 62.

In passing from one condition to the other, the amplification changes from a minimum gain level indicated by the line 63 to a maximum level represented by the line 64. When the tube enters the zero bias range, the series resistance of the resistors 31, 51 and 50 cause the resulting grid current to provide a relatively high potential drop as a limiting control means in the circuit between the grid and the cathode.

In a given amplifier for phonograph or radio operation, signal input levels above a certain high value represented by the input level at the line 62 are unnecessary and provide a relatively slight amount of volume expansion, while below a certain low level of input amplitude represented by the line 61, the volume expansion is relatively slight. The adjustable control element 36-38 in the input circuit of the volume expander may be adjusted to provide an applied signal and a rectified control potential for operating the amplifier in the range most effective for volume expansion, that is, in the range represented between the lines 61 and 62 of Fig. 3.

It has been found that not all types of audio frequency signals or recordings are adapted for volume range expansion. Therefore, it is desirable to provide a position of adjustment for the control means 36-38 at which the expander may be rendered ineffective. For this purpose, the control arm 38 is arranged to contact the low potential or ground side of the signal input system through an auxiliary ground contact 66, thereby insuring that no control signal is supplied to the control amplifier 41 and to the volume expander diode 48.

If no other provision for cutting off the expander were made, this would result in the amplifier in the expander "off" position being operated at its lowest gain as indicated by the line 63 of Fig. 3. In the expander "off" position, the gain may be increased to the maximum value indicated by the line 64 in Fig. 3 by means of a connection such that substantially zero bias is applied to the gain control grid 30. However, both arrangements have certain disadvantages. The first has the disadvantage that operating at minimum gain causes the amplifier to have a relatively low output on weak signals or recordings, while the second has the disadvantage that operating at maximum gain will cause the output to increase abruptly through the entire expanded range when the expander control is turned off, causing objectionable noise in the output device.

In order to avoid the disadvantages encountered with either method of operation referred to, with a given minimum and maximum condition of gain established, for example as indicated at 63 and 64 in Fig. 3, a fixed bias condition for the expander amplifier is so chosen for the "off" position of the expander control, the amplification or gain lies substantially midway between the minimum and maximum values of the expansion range as indicated by the line 65 in Fig. 3. To this end, in the amplifier shown, a switch 67 is provided in connection with the expander control element 38 and connected therewith as indicated by the dotted connection 68 to close the switch 67 when the contact 38 engages the contact 66 in the expander "off" position. The switch controls a circuit comprising a lead 69 connected to the amplifier cathode 22 and a lead 70 connected through a series resistor 71 to a point 72 on the resistor network 31, 51, 53 between the resistors 31 and 51. This point is provided with a filter capacitor 13 to ground. A bypass capacitor 14 is provided for the bias source 20-21 as indicated at 74.

Referring to Fig. 2 along with Fig. 1, the circuit arrangement of Fig. 1 is rearranged and simplified, whereby it may be seen that when the switch 67 is closed, the gain control grid 30 is connected to a tap point which is the terminal 72 on a potentiometer resistor comprising the resistors 71, 51 and 50 across the initial bias potential source 20-21. Since the resistor 71 may have a value of substantially 2.7 megohms and the resistors 31, 51 and 50 may have a resistance of 560,000 ohms each, the tap point 72 is substantially two-thirds of the way down on the potential source 20-21, and as this source comprises a variable resistor at 21, the potential may be adjusted to any suitable value to bring the expander controlled amplifier gain substantially midway of its minimum and maximum values, when the expander is turned off.

With this arrangement, the expander may be cut into operation or turned off as desired during the playing of a record or during a radio program without appreciable change in the gain of the amplifier and without noticeable and undesirable abrupt change in volume. At the same time, by making the input signal control means 36-38 for the expander effective over a limited range by the limiting resistors 35 and 37, to permit the expander to respond in an operating range between signal loads corresponding to strong or relatively high amplitude passages on high average amplitude and low average amplitude records or radio programs, the full operating range of the expander control may be utilized. This is provided by the series controlling circuit comprising the fixed resistors 35 and 37 which render the expander ineffective over the initial bias and zero bias control ranges, while the control element 36 is effective to provide full or extended control for proper expander action over the range therebetween.

With the expander amplifier in operation, the average signal amplitude to be applied to the expander amplifier channel by adjustment of the potentiometer contact 38 is determined by the average signal strength of the received signal or the average amplitude level of the record being played.

The range of control provided by the potentiometer element 36-38 is such that with the contact 38 adjusted for minimum signal input 75 to the expander channel, that is, with the contact

38 at the lower end of the resistor element 36 as viewed in the drawing, for minimum dynamic expansion, the relative resistance values of the potentiometer drop producing elements 35, 36 and 37 are such that volume range expansion action takes place in response to signals of relatively high amplitude above a normal range of high average amplitude signals or in response to relatively high amplitude passages in loud or high average amplitude records.

When the volume expander control device is adjusted with the contact 38 at the upper end of the resistor 36 as viewed in the drawing, for maximum dynamic expansion, the maximum signal input from the signal source is provided for the expander amplifier channel, and is such that with low average amplitude or weak signals, a relatively strong or high amplitude passage therein will effect a volume expansion action, that is, the expander circuit will operate on a loud or relatively high amplitude passage on a weak or low average amplitude record. For intermediate average signal amplitude values, the expander control device is adjusted with the contact 38 at suitable intermediate positions as required.

By limiting the expander action to signals above a predetermined relatively low amplitude and below a predetermined relatively high amplitude, the range of control of the device 36-38 is extended to cover the full range of movement provided by the device in its control range and overloading and distortion are prevented.

I claim as my invention:

In an audio frequency amplifier, the combina- 35

tion of a volume range expander circuit, variable signal input potentiometer means for said circuit, a signal amplifier tube having an input electrode connected with said potentiometer means, a diode rectifier coupled to said tube and having a cathode operative at a high signal potential whereby said diode is inverted, an output resistor for said diode rectifier, a combined amplifier and volume expander tube for said amplifier having a gain-control grid and a cathode, self-bias means in circuit with the cathode providing a potential source for establishing a predetermined condition of low gain for said last-named amplifier tube, means for applying to said grid a biasing potential from said source and said diode rectifier in opposition, said last named means including grid current limiting resistors, potential drop producing means in circuit with said potentiometer means serially on each side thereof for extending the effective control range for volume range expansion substantially over the full variation range thereof and for establishing a predetermined condition of maximum gain for signal input voltages ranging above a predetermined low peak amplitude and below a predetermined high average amplitude, and means for establishing on said gain-control grid a biasing potential effective to set the gain of said signal amplifier at a level substantially midway between said maximum and minimum gain, comprising a switch connection between said cathode and a tap intermediate between two of said grid current limiting resistors.

PAUL F. G. HOLST.
